UNITED STATES PATENT OFFICE.

JOSIAH N. JONES, OF WORCESTER, ASSIGNOR OF ONE-HALF TO F. F. RAYMOND, 2d, OF NEWTON, MASSACHUSETTS.

PICKER-LAG.

SPECIFICATION forming part of Letters Patent No. 269,060, dated December 12, 1882.

Application filed March 13, 1882. (No model.)

To all whom it may concern:

Be it known that I, JOSIAH N. JONES, of Worcester, in the county of Worcester and State of Massachusetts, a citizen of the United States, have invented an Improvement in Picker-Lags, of which the following is a full, clear, and exact description, reference being had to the accompanying drawings, forming a part of this specification, in explaining its nature, in which—

Figure 1 is a perspective view of a part of a lag containing my invention, and Fig. 2 is a section illustrating the construction thereof.

This invention is an improvement upon that described in my Letters Patent No. 224,545, dated February 17, 1880; and it consists in a picker-lag having interposed between the metallic plates thereof a cheap and preferably comparatively light material, like leather-board, straw-board, pasteboard, wood, &c., whereby the metal plates may be made thinner, and therefore more easily punched, the lag made lighter, and its cost materially cheapened.

In the drawings, *a a'* are the metal plates of the lag; *b*, an interposed layer of leather-board, straw-board, pasteboard, wood, or other suitable material of like nature lightly compressed between the metal plates, which are riveted together. *c* are the wooden bushings. *d* are the teeth.

In making the lag the holes or perforations in the plates are formed by punching, and the plates are then curved in any suitable way to the proper curvature. The outer plate is also formed at its ends to provide the depression *e*, whereby the ends of the two plates may be brought in contact and a space for the filling provided. Non-metallic filling of proper thick-

ness is then interposed between the two plates and the plates riveted solidly together. Holes 40 corresponding to those formed in the metal plates are then formed in the interposed material. Non-metallic bushings are then driven into the holes and the teeth driven through them. By this construction not only is the lag 45 lightened and cheapened, but the use of a non-metallic interposed layer of less density than the metal plate permits the part of the bushing held or enveloped by it to expand upon the driving of the teeth, so that a shoulder or enlargement upon each bushing is formed between the metal plates, and the bushings are thereby effectually locked in place between them.

With the construction described in the patent referred to, in order to obtain a sufficient bearing for the bushings, it is necessary to use much thicker metal plates than is needed for strength, while with this invention I make the plates as thin as due regard for strength will allow, and obtain the necessary thickness for the bushing-bearings by means of interposed non-metallic layers.

Having thus fully described my invention, I claim and desire to secure by Letters Patent 65 of the United States—

A picker-lag comprising the metal plates provided with perforations *a a'*, the interposed non-metallic layer *b*, the bushing *c*, and the teeth *d*, all combined substantially as and for 70 the purposes described.

JOSIAH N. JONES.
